(57) **CLAIM**

The ornamental design for a purge cassette of a catheter pump, as shown and described.

DESCRIPTION

1. Purge cassette of a catheter pump
FIG. 1.1 is a front perspective view of a purge cassette of a catheter pump showing my new design;
FIG. 1.2 is a rear perspective view thereof;
FIG. 1.3 is a front elevation view thereof;
FIG. 1.4 is a rear elevation view thereof;
FIG. 1.5 is a left side elevation view thereof;
FIG. 1.6 is a right side elevation view thereof;
FIG. 1.7 is a top plan view thereof; and
FIG. 1.8 is a bottom plan view thereof.
